FILE ENVELOPE

Claude R. Middleton, Detroit, Mich.

Application December 29, 1931
Serial No. 583,638

5 Claims. (Cl. 129—16.7)

This invention relates to file envelopes and the object of the invention is to provide an envelope in which booklets, stock records, order blanks or other printed matter may be mailed, 5 the device being arranged so that the flap carries the letter concerning the mailed material and the envelope carries the material, the letter being separable from the envelope and when separated leaving a file envelope with a filing 10 tab carrying indicia as to the contents of the envelope.

One of the particular objects of the invention is to provide an envelope which may be utilized in mailing third class matter and having a flap 15 separable from the envelope to provide a filing pocket having an extending index tab on which indicia may be printed.

A further object of the invention is to provide an envelope of the character described which 20 may be readily opened by the postal authorities for inspection.

Another object of the invention is to provide an envelope having a pocket for printed matter and having a flap carrying a letter concerning 25 the printed matter, the said flap being foldable to provide a closure for the pocket and the material of the envelope being perforated so that the letter flap may be separated therefrom, the perforations being arranged to leave a tab attached to the pocket, said tab carrying indicia concerning the contents of the pocket and the 30 pocket and index tab being usable as a file pocket in a filing cabinet.

These objects and the several novel features 35 of the invention are hereinafter more fully described and claimed and the preferred form of construction by which these objects are attained is shown in the accompanying drawing in which—

40 Fig. 1 is a perspective view of a file envelope, embodying my invention, ready for mailing.

Fig. 2 is a perspective view showing the file envelope open for inspection.

Fig. 3 is an elevation of the file pocket after 45 the letter flap has been separated therefrom.

Fig. 4 is an enlarged section taken on line A—A of Fig. 3.

The device is formed from a paper sheet and comprises a center section having integral end 50 flaps 1 as shown in Fig. 2. The portion 2 is foldable on the center section as shown in Fig. 2 and the flaps 1 are turned thereover and glued to the portion 2 thus forming a pocket in which pamphlets or other printed matter 3 may be 55 inserted. The letter flap 4 is folded on the

dotted line 5 to form a closure flap for the file pocket and the letter flap is provided with an aperture 6 having a re-enforcing member 7 thereabout through which the metal clasp 8 may be inserted. This metal clasp 8 is secured in 60 the portion 2 of the envelope and provides a means for closing the envelope as will be understood from Fig. 1. The center section of the envelope is provided with a series of perforations 9 on a line parallel with the top and bottom of 65 the envelope and spaced from the fold 5 on which the letter flap folds over the portion 2. The perforations 9 are carried through to an index tab 10 formed by the die cut slots 11 at the edges and by the perforations 12 at the top 70 which are coextensive with the fold 5 of the letter flap.

In use the letter flap provides a space on which a letter may be written concerning the contents of the file pocket. The pocket may contain 75 order blanks, cards, folders, sales pamphlets, advertising matter or any other matter of similar nature which can be conveniently placed in the envelope. The portion 2 of the envelope pocket also lists the contents of the pocket on the face 80 thereof and the flap 4 when folded over the pocket is secured in place by the clasp 8 as shown in Fig. 1. The outside of the flap 4 carries the return address of the company mailing the envelope together with sales slogans or contents 85 of the envelope. This side of the flap 4 shown in Fig. 1 is also utilized for the address of the person to whom the envelope is sent. The receiver upon opening the envelope may read the letter on the inner face of the flap 4 concerning 90 the contents of the file pocket and if the contents are to be kept for future reference the user tears the letter flap 4 off on the perforations 9 and 12 which will leave the index tab 10 extending upwardly from one edge of the file 95 pocket. This index tab refers to the contents of the file pocket and the file pocket may be placed in a standard file cabinet under the proper index. In this manner, the contents of the file pocket are always available for future 100 reference and thus insures the receiver having the material at hand when the need arises.

From the foregoing description, it becomes evident that the device is very simple and efficient in operation, is very useful in filing the 105 contents for future reference, is readily accessible in a file and provides a device which accomplishes the objects described.

Having thus fully described my invention, its utility and mode of operation, what I claim and 110

desire to secure by Letters Patent of the United States is—

1. In a file envelope, a paper sheet arranged to provide a rectangular pocket open at one side, 5 the sheet being provided with a fold line in spaced relation with the open side of the pocket to provide a flap foldable over the pocket to close the same, the sheet being also provided with perforations extending parallel to the fold 10 line between the fold line and the open side of the pocket, the perforations at one side of the sheet extending upwardly to the fold line to provide an index tab having an upper edge co-extensive with the fold line and the flap being 15 separable from the pocket along the perforations to leave the index tab extending above the open side of the pocket.
2. In a file envelope, a paper sheet arranged to provide a rectangular pocket open at one side, 20 the sheet being provided with a fold line in spaced relation with the open side of the pocket to provide a flap foldable over the pocket to close the same, the sheet being also provided with perforations between the fold line and the 25 open side of the pocket and extending parallel with the fold line, the perforations being arranged to provide an index tab having an upper edge co-extensive with the fold line and the flap being separable along the perforations 30 with the index tab extending above the open side of the pocket.
3. In a file envelope, a paper sheet arranged to provide a rectangular pocket open at one side and having a portion extending from the open 35

side of the pocket, the extending portion being provided with a fold line in spaced parallel relation with the open side of the pocket to provide a flap foldable over the pocket, the sheet being also provided with perforations between the pocket and the fold line, the perforations being arranged to provide an index tab having an upper edge co-extensive with the fold line and the flap being separable from the pocket on the said perforations.

4. In a file envelope, a paper sheet arranged to provide a rectangular pocket and having a portion extending from one side of the pocket, the sheet being provided with a fold line in spaced parallel relation with the side of the pocket to provide a flap foldable over the pocket, the sheet being also provided with perforations between the fold line and the side of the pocket and extending parallel with the fold line, the perforations being arranged at one end to form an index tab when the flap is torn off, the upper edge of the index tab being co-extensive with the fold line.

5. In a file envelope, a paper sheet arranged to provide a rectangular pocket and having a portion extending from one side of the rectangular pocket, the extending portion being provided with a fold line in spaced relation with the side of the pocket to provide a flap foldable over the pocket, the sheet being perforated between the pocket and the fold line and the perforations being arranged to form an index tab having an upper edge co-extensive with the fold line.
